United States Patent Office

Des. 193,281
Patented July 24, 1962

193,281

BOTTLE

David G. Hills, Bloomfield, Conn., assignor to Plax Corporation, Bloomfield, Conn., a corporation of Delaware

Filed Jan. 23, 1961, Ser. No. 63,661

Term of patent 14 years

(Cl. D58—6)

FIG. 1

FIG. 2

FIG. 3

FIG. 1 is a top plan view of a bottle, showing my new design;

FIG. 2 is a front elevational view; and

FIG. 3 is a side view of FIG. 2.

The dominant features of the design reside in the portions shown in the solid lines on the drawing.

I claim:

The ornamental design for a bottle, substantially as shown and described.
